STOP MOTION FOR LOOMS, ETC.

Julia Kyner, Zionsville, Pa.

Application February 6, 1946, Serial No. 645,832

12 Claims. (Cl. 139—353)

1

This invention relates to stop motions for textile machinery, wherein single yarns or threads, or a multiplicity thereof, are normally adapted to be drawn or pulled in a predetermined direction axially or longitudinally thereof and maintained under a substantially uniform predetermined tension as each yarn travels axially between two relatively distant points, as will be found in winding, twisting, warping, knitting, weaving, and other machinery employed in the textile industry.

The present invention relates particularly to a device for detecting the development of excessive slack in a running thread or yarn, or the breaking of the yarn under excessive tension, or for other reasons such as weak spots present in the structure of the yarn itself, etc.

In the accompanying drawing:

Fig. 1 is a diagrammatic perspective view, partly in section, illustrating the general construction and principles of operation of the device;

Fig. 2 is an enlarged view, partly in section, of the detecting device per se;

Fig. 3 is a face view of the structure illustrated in Fig. 2, showing the traveling yarn in cross section; and

Figs. 4 and 5 illustrate modifications of the invention.

In Fig. 1 of the drawing, a thread or yarn *x* is shown as being drawn from a supply package, such as a spool or bobbin *y*, which is rotatably mounted on a supporting spindle *z*. Any suitable friction means may be employed to retard the rotation of the package *y* on its supporting spindle *z* to place the yarn *x* under predetermined tension as it is drawn from the package *y*. As such friction devices are common in the art and form no part of the present invention, no illustration thereof has been made in the present drawing.

The yarn or thread *x* is adapted to be drawn longitudinally in the direction of the arrows *a*, *a*, under a substantially uniform tension, by the weaving of the thread *x* in a loom, the formation of the yarn into loops in a knitting machine, or the winding of the thread onto a warp beam, etc., against the action of the friction device which retards the rotation of said package *y*, as previously noted.

Preferably, in the course of its axial travel, the yarn *x* is laid over and is adapted to bear on and be supported and guided by a pair of relatively spaced rods or rollers *b*, *b*, whereby a predetermined section *xl* of the traveling yarn *x* is maintained in a substantially straight line.

2

The detector element 1 of the present invention comprises a piece of highly resilient metal such, for example as beryllium copper of spring quality, bent into the general shape of a sickle 5 and consisting of an arcuate body section 2, a substantially straight leg portion 3 connected by a short radius curved or fillet portion 4, by which flexibility between the parts 2 and 3 is provided, and which will permit said parts to move toward or away from each other under operating conditions hereinafter described. The leg portion 3 of the detector 1 is connected by a small radius curved portion 5 with a straight foot portion 6 which is adapted to be rigidly mounted in a support 7.

The detecting device 1, and particularly the arcuate head portion 2 thereof, is adapted to be mounted and to operate between a pair of parallel reed or sley blades or fingers 8, 8, which 20 are normally adapted to limit lateral movement of the running thread or yarn *x* as it travels in the direction of the arrows *a*, *a*. The lower end portions of the guide fingers 8, 8 are also rigidly mounted in the support 7 in the same plane 25 with or in a plane parallel to and preferably immediately adjacent the plane of the foot 6 of the detector 1. While the foot 6 of the detector 1 and the ends 9, 9 of the fingers 8, 8 may be secured to the support 7 in any desired manner, 30 it is preferable to cast the support 7 in the form of a block around the foot 6 and ends 9, 9, of the fingers 8, 8, whereby these elements are maintained in rigid fixed relation to each other.

Intermediate the fingers 8, 8, the arcuate body 35 portion 2 of the detector 1 is bent into a V-shape cross sectional form, to provide a trough 10 for receiving and supporting the yarn *x*. The diverging arms 11, 11 of the V-shape 1 trough 10, in each instance, substantially fill the space 40 between the fingers 8, 8 with just sufficient clearance therebetween to prevent binding of the body portion 2 of the detector 1 between the laterally spaced fingers 8, 8.

In instances where a plurality or multiplicity 45 of yarns *x* are arranged side by side, such as the warps of a loom or a warp knitting machine, etc., there would be a detector 1 for each yarn *x*. In such instances there would be at least a corresponding number of sley points 8, 8. In such 50 instances the plurality of detectors and associated sley points 8, 8 would be divided into groups and each group would be leaded into a single block 7, if desired.

The supporting blocks 7, in which the detectors 1, 1 and fingers 8, 8 are rigidly secured, are

adapted to be secured to a suitable support, such as a bus bar 12, as by a bolt or screw 13, for example, with the bus bar 12 grounded in any suitable manner in the machine in which the detectors 1, 1 are employed, said bus bar forming one side of an electric circuit in which the detector 1 is included.

The second side of the electrical circuit is formed by the bus bar 14 which is suitably supported in the machine by a plurality of insulator lugs or brackets 15.

In the present instance, the bus bar 14 is of L-shaped cross section with one leg or flange 16 thereof secured in the insulator lugs 15 and with the edge 17 of the second leg 18 of the bus bar disposed adjacent the small radius fillet or neck portion 4 of the detector 1.

The bus bar 14 is adapted to be connected by a conductor 19 with one side of a relay 20 which constitutes a part of an electrical stop motion circuit forming no part of the present invention. The second side of the relay circuit is grounded in the machine, as indicated at 21, to which the bus bar 12 is also grounded.

In operation, the tension of the yarn x as it is running longitudinally through and in contact with the base of the V-shaped trough 10, presses the body 2 toward the foot 6, flexing the elements 2 and 3 at the fillets 4 and 5; and the frictional drag of the yarn in the groove 10 rocks the detector 1 in the direction of travel of the yarn, flexing it at the fillet 5, thereby holding the neck 4 out of contact with the edge 17 of the leg 18 of the bus bar 14, thereby forming a circuit opening gap G between the detector 1 and the bus bar 14.

Should the thread or yarn x break or become excessively slack, the detector 1 will assume the position shown in broken lines in Fig. 2, with the neck or fillet portion 4 of the detector 1 making contact with the edge 17 of the bus bar 14, thereby closing the detector circuit and causing the relay 20 to function and effect stopping of the machine in which the yarn x is operating.

In instances where a plurality of detectors 1 are employed and cast in each of the blocks 7, the groups of detectors 1, 1 may be punched, cut, or otherwise formed from a single strip of metal, as a comb, with a single foot 6a adapted to be leaded into the block 7 adjacent the ends 9, 9 of the sley points 8, 8 as shown in Fig. 4; and the foot 6b may be corrugated, as shown at 26 in Fig. 5, to receive the points 8, 8 prior to casting of the block, if desired.

I claim:

1. A slack and breakage detector for an axially running normally tensioned rectilinear yarn, comprising an inherently resilient unitary element including a foot a leg and a body portion successively interconnected and relatively angularly arranged in a common plane coincident with said yarn, guide means at opposite sides respectively of said body portion to insure positioning and retention of said yarn thereon, means for rigidly supporting said foot in predetermined relation to said yarn to effect flexing of said element to and retention of said element in an inactive position in said plane by said yarn when running normally therein, and means intersecting said plane for engagement with said element under reactive inherent reverse flexing thereof when released by slack or breakage developing in said yarn, whereby the running of said yarn will be discontinued.

2. A slack and breakage detector for an axially running normally tensioned rectilinear yarn,

comprising an inherently resilient unitary element including a foot a leg and a body portion successively interconnected and relatively angularly arranged in a common plane coincident with said yarn, said body portion being grooved longitudinally in said plane to receive said yarn, means for rigidly supporting said foot in predetermined relation to said yarn to effect flexing of said element to and retention of said element in an inactive position in said plane by said yarn when running normally therein, and means intersecting said plane for engagement with said element under reactive inherent reverse flexing thereof when released by slack or breakage developing in said yarn, whereby the running of said yarn will be discontinued.

3. A slack and breakage detector for an axially running normally tensioned rectilinear yarn, comprising an inherently resilient unitary element including a foot a leg and a body portion successively interconnected and relatively angularly arranged in a common plane coincident with said yarn, said body portion being grooved longitudinally in said plane to receive said yarn, guide means at opposite sides respectively of said body portion to insure positioning of said yarn in the longitudinal groove of said body portion, means for rigidly supporting said foot in predetermined relation to said yarn to effect flexing of said element to and retention of said element in an inactive position in said plane by said yarn when running normally therein, and means intersecting said plane for engagement with said element under reactive inherent reverse flexing thereof when released by slack or breakage developing in said yarn, whereby the running of said yarn will be discontinued.

4. A slack and breakage detector for an axially running normally tensioned rectilinear yarn, comprising an inherently resilient unitary element including a foot a leg and a body portion successively interconnected and relatively angularly arranged in a common plane coincident with said yarn, said body portion being longitudinally curved and grooved in said plane to receive and retain said yarn therein, means for rigidly supporting said foot in predetermined relation to said yarn to effect flexing of said element to and retention of said element in an inactive position in said plane by said yarn when running normally therein, and means intersecting said plane for engagement with said element under reactive inherent reverse flexing thereof when released by slack or breakage developing in said yarn, whereby the running of said yarn will be discontinued.

5. An inherently resilient yarn contacting element comprising a longitudinally arcuate body portion, of substantially V-shaped in cross-section adapted to receive and guide a strand of yarn, a leg portion connected at one of its ends to one end of said body portion and disposed at an acute angle to said body portion in a common plane therewith, and a foot portion connected to the opposite end of said leg portion for mounting said element to afford flexing of said body and leg portions relative to each other and with respect to said foot portion.

6. An inherently resilient yarn contacting element comprising a longitudinally arcuate body portion grooved substantially throughout its length to receive and prevent lateral shifting of a strand of yarn relative thereto, a leg portion connected at one of its ends to one end of said body portion and disposed at an acute angle to said

body portion in a common plane therewith, and a foot portion connected to the opposite end of said leg portion for mounting said element to afford flexing of said body and leg portions relative to each other and with respect to said foot portion.

7. An inherently resilient yarn contacting element comprising a longitudinally arcuate body portion of V-shaped cross section, a leg portion of rectangular cross section connected at one of its ends to one of said body portion and disposed at an acute angle to said body portion in a common plane therewith, and a foot portion connected to the opposite end of said leg portion for mounting said element to afford flexing of said body and leg portions relative to each other and with respect to said foot portion.

8. An inherently resilient yarn contacting element comprising a longitudinally arcuate body portion of substantially V-shape in cross-section adapted to receive and guide a strand of yarn, a leg portion connected at one of its ends to one end of said body portion and disposed at an acute angle to said body portion in a common plane therewith, and a foot portion connected to the opposite end of said leg portion and disposed at an obtuse angle with respect thereto and disposed within said common plane for mounting said element to afford flexing of said body and leg portions relative to each other and with respect to said foot portion.

9. An inherently resilient yarn contacting element comprising a longitudinally arcuate body portion of substantially V-shape in cross-section adapted to receive and guide a strand of yarn, a leg portion connected at one of its ends to one end of said body portion and disposed at an acute angle to said body portion in a common plane therewith, a short radius fillet portion of rectangular cross section intermediate said body and leg portions and connected at its opposite ends respectively thereto, and a foot portion connected to the opposite end of said leg portion for mounting said element to afford flexing of said body and leg portions relative to each other and with respect to said foot portion.

10. A structure comprising a plurality of yarn contacting elements arranged laterally spaced relation and each including a longitudinally arcuate body portion, a leg portion connected at one of its ends to one end of said body portion, and a common foot portion connected to the opposite end of each of said leg portions of said plurality of said elements, said common foot portion being

corrugated and offset between said leg portions for the purpose described.

11. A slack and breakage detector for an axially running normally tensioned rectilinear yarn, comprising an inherently resilient unitary element including a foot, a leg and a body portion successively interconnected with said body portion being grooved longitudinally to receive said yarn, means for rigidly supporting said foot in predetermined relation to said yarn to effect flexing of said element to and retention of said element in an inactive position by said yarn when running therein, and means engageable by said element under reactive inherent reverse flexing thereof when released by slack or breakage developing in said yarn, whereby the running of said yarn will be discontinued.
12. A slack and breakage detector for an axially running normally tensioned rectilinear yarn, comprising an inherently resilient unitary element including a foot, a leg and a body portion successively interconnected and relatively angularly arranged with said body portion being grooved longitudinally to receive said yarn, guide means at opposite sides respectively of said body portion to insure positioning of said yarn in the longitudinal groove of said body portion, means for rigidly supporting said foot in predetermined relation to said yarn to effect flexing of said element to and retention of said element in an inactive position by said yarn when running therein, and means positioned for engagement by said element under reactive inherent reverse flexing thereof when released by slack or breakage developing in said yarn, whereby the running of said yarn will be discontinued.
